Patented Jan. 1, 1918.

UNITED STATES PATENT OFFICE.

LUIS DEL RIVERO, OF LOS ANGELES, CALIFORNIA.

SIPHON-BOTTLE HEAD.

1,252,313.

Specification of Letters Patent. Patented Jan. 1, 1918.

Application filed June 23, 1916. Serial No. 105,494.

To all whom it may concern:

Be it known that I, LUIS DEL RIVERO, a subject of the King of Spain, residing at Los Angeles, in the county of Los Angeles 5 and State of California, have invented new and useful Improvements in Siphon-Bottle Heads, of which the following is a specification.

This invention relates to a siphon bottle 10 and particularly pertains to a valve head therefor.

It has been a matter of considerable difficulty to charge siphon bottles of the ordinary construction due to the fact that the 15 liquid necessarily has to pass into the bottle through the same orifice that the air within the bottle passes out and as bottles are commonly constructed are provided with a stem extending the length of the bottle, it 20 has required considerable manipulation of the contents of the bottle to fill it completely and remove the air which is trapped therein.

It is the object of this invention to provide a siphon bottle which may be readily 25 filled by means of a semi-automatic filling machine in such manner as to obviate handling of the bottle during the filling operation.

Another object is to provide means for 30 allowing a siphon bottle to be readily filled without possibility of air being trapped therein and by which the liquid may be introduced continuously into the bottle under pressure as it displaces the air.

Another object of this invention is to provide 35 automatic valve means which may be actuated by the pressure of a fluid and will, when so actuated, allow the fluid to enter the bottle through the valve head without 40 interfering with the siphon valve ordinarily provided therefor and which will permit of the bottle being filled in either an upright or an inverted position.

Another object is to provide simple means 45 for confining a liquid under pressure within the bottle, which means will not act upon the siphon valve control and will insure that the liquid may be only drawn through the siphon valve.

Another object is to provide a siphon 50 bottle valve head which allows the bottle to

be readily filled in a continuous operation and insures against waste of the liquid as is common in present practice.

It is a further object to provide a siphon 55 bottle head which is simple in its construction and which may be easily manipulated to fill the bottle or to discharge the liquid therefrom.

Other objects will appear hereinafter. 60

The invention is illustrated in the accompanying drawings in which:

Figure 1 is a fragmentary view of a siphon bottle showing it provided with the improved head and illustrating in vertical 65 section the detail thereof.

Fig. 2 is a fragmentary view of the bottle head and particularly illustrates the vent or filling conduit.

Fig. 3 is a diagrammatical view in side 70 elevation of the siphon bottle as being filled while in an upright position.

Fig. 4 is a view similar to Fig. 3 showing the bottle as being filled while in an inverted position. 75

Referring to the drawings more particularly, 10 indicates a siphon bottle which is commonly formed of glass and which has mounted upon its neck 11 a siphon valve head 12. The valve head, as particularly 80 illustrated in the drawings, is provided for two purposes, one, to furnish valve controlled filling or vent means, and the other to provide a valve controlled siphon outlet. The present invention is particularly involved in the construction of the filling or vent valve as shown in detail in Fig. 2 of 85 the drawings.

The valve head 12 is formed with a cylindrical body portion 13 which is enlarged at 90 its lower end to provide a threaded cap 14 for engagement with a metallic sleeve or collar 15 which fits around the neck 11 of the bottle and is clamped thereupon by the threaded cap 14 as it is screwed in position 95 upon the sleeve. The cap 14 has its upper extension formed with a cylindrical externally threaded member 16 within which a siphon valve chamber 17 is formed. The chamber 17 extends longitudinally of the 100 body portion 13 and provides that a valve head 18 may be held by means of an expa-

sion coil spring 19 upon a packing ring 20. The packing ring encircles an opening communicating with a faucet 21. The valve head 18 is provided with a stem 22 which 5 extends upwardly and into a cylindrical bore 23 where it is engaged by a nut 24 adapted to be reciprocated within the bore by a thumb lever 25 fulcrumed in a suitable manner in the wall of the bore. A pair of 10 packing washers 26 and 27 are superimposed one upon the other at the bottom of the bore 23 and act to prevent leakage of the fluid around the valve stem. The washers are held in place by a coil spring 19 which acts against them and upholds the nut 24 against the lower face of which it bears. The foregoing description refers 15 particularly to the faucet or siphon valve construction whereby the discharge of the liquid is controlled and which construction 20 is now generally in use in siphon bottles.

Reference being had to Fig. 2 in which the vent or filling valve is illustrated, it will be seen that a conduit 28 is formed within 25 the body of the bottle head and extends the length thereof. This conduit provides communication between the cap 41 and the upper end of the bore 23. The upper end 29 of the conduit communicates with a counter-bore 30 formed within the upper opened end of the bore 23. A disk 31 is provided to seat at the bottom of said counter-bore and acts as a partition wall between the counter-bore and the main bore 23 as well 35 as a mounting for a disk valve 32 held by a compression spring 33 against a packing ring 34. The packing ring 34 is fixed in position within an annular V-shaped groove 35 which occurs at a point slightly above 40 the opening 29 of the conduit 28. A ring nut 36 is provided and holds the packing ring in position against the pressure of the spring 33 beneath the disk valve 32. The nut 36 is formed with a central communicat- 45 ing opening 37 for a purpose which will be hereinafter set forth.

The bottle is provided with the usual siphon stem 38 suitably secured by a metallic fitting 39 to the cylindrical threaded 50 extension 16 of the bottle head and thus establishes communication between the bottle at its lowermost end with the spout 21 when the valve head 18 is in its lowermost position.

55 In assembling the bottle and its valve head, it is first necessary to place the ring 20 in position upon its seat and insert the stem of the valve member 18 therethrough. The packing washers 26 and 27 are positioned around the stem and within the bore 23. After the spring 19 has been placed over the stem and seated between the washer 26 and the nut 24, the thumb lever is mounted within the bore. The lever is adapted 60 to bear upon the extension 40 of the nut

24. When the siphon stem fitting 39 is screwed into position, the siphon valve is in its complete assembled condition.

The filling or vent valve mechanism is then assembled within the body 13 by first placing the partition disk 31 within the counter-bore and mounting the disk valve 32 reciprocally thereupon. The packing ring 34 is next placed in position and held by the nut 36, thus completing the assembly 75 of the vent valve.

The bottle may be filled in two ways when equipped with this improved valve head. However, it is believed preferable to fill it while in its upright position and this operation will be first set forth. It may be also stated that the bottle may be filled by hand or a machine and in either case a suitable filling cap 41 will be clamped in connection with the bottle and in communication with a supply of liquid adapted to be subjected to pressure. In the preferred form, the member 41 is positioned over the mouth of the faucet 21 after which the valve head 18 is moved downwardly from its seat 20 and a gas charged liquid is directed through the siphon stem into the bottle under suitable pressure. It is evident that as the level of the water rises in the bottle, the atmospheric pressure at the top of the bottle will be increased. To prevent the liquid from being retarded in its flow the disk valve 32 is suitably opened by being manually depressed by an instrument extending through opening 37 in the nut 36, so that the air within the bottle may be vented through the passage 28 and out to the atmosphere through the opening 37 in the nut 36. As the liquid enters the bottle, some of the gas therein is liberated which will occupy 105 the space above the liquid when the bottle is about two-thirds full. The valve 32 is then closed and the bottle filled with the liquid under pressure.

In filling the bottle by the second method, 110 the bottle is inverted and the cap 41 applied over the end of the valve head. The pressure of the liquid against the valve disk 32 moves the disk inwardly and causes it to uncover the opening 29 of the conduit 28 and thus allow the liquid to pass through the conduit 28 into the bottle. Simultaneously with the inward movement of the liquid into the bottle, the thumb lever 25 is operated to unseat the valve head 18 and 115 allow the air to pass from the bottom of the bottle, which, in this case, is uppermost, through the stem and out the faucet 21. After the bottle has been filled about two-thirds full with liquid the valve head 18 is 120 re-seated and the liquid contents subjected to an excessive charging pressure as before described. When the bottle head is removed 125 from the filling cap 41 it will act automatically to seat the disk valve 32 upon the 130

packing ring 34 and thus close the conduit 28 in a positive manner.

It will thus be seen that the siphon bottle here disclosed may be quickly and continuously filled without handling the bottle during the filling operation and without trapping air therein.

I claim:

In a siphon bottle head, a cylindrical body 10 having a central cylindrical bore extending downwardly from the upper end of the body and terminating therein, the end wall of said bore being formed with a small central opening, a valve plunger, the stem of which 15 is adapted to reciprocate through the small central opening of the body, a seat against which said valve member is adapted to bear, a coil spring mounted within said central bore and adapted to hold the valve against 20 its seat, an actuating lever by which the valve may be relieved from its seat in opposition to said spring, a siphon spout in communication with the small central bore of the cylindrical body and which is controlled 25 by said plunger valve, a siphon tube mounted beneath the plunger valve and in com-

munication therewith, said tube being disposed in longitudinal alinement with the valve stem and the central axis of the cylindrical body bore, a mounting sleeve formed 30 integral with said cylindrical body and adapted to encircle the siphon tube in a manner to permit the head to be secured upon the mouth of the bottle, a partition wall positioned within the upper end of the cylindrical bore of the body member, a disk valve 35 yieldably mounted upon one side of said partition wall, an externally threaded hollow nut mounted within the end of the cylindrical bore of said body member, and 40 a passage-way formed within the side wall of said cylindrical body and adapted to establish communication between the interior of the bottle upon which the head is mounted and the external space upon application of pressure to the auxiliary disk valve 45 which is held in closed position by means of a compression spring surrounding the stem of said valve.

In testimony whereof I have signed my 50 name to this specification.

LUIS DEL RIVERO.
